SPLIT VALVE SPRING KEEPER INSERTER

John Vold, Wiggins, Colo.

Application October 11, 1949, Serial No. 120,695

2 Claims. (Cl. 29—249)

1
This invention relates to improvements in automobile engine repair tools, and more particularly to an implement for use in inserting valve spring keys of the split type.

A main object of the invention is to provide a novel and improved valve spring key-inserting tool which is simple in design, rugged in construction, which is very easy to manipulate, and which securely holds and positively controls the placement of the two parts of the key in position for insertion, enables the two part to be rotated apart for positioning upon the valve stem, and which is readily removed from the mounted key segments, leaving said segments in locking position upon the valve stem.

A further object of the invention is to provide an improved valve key-inserting tool which readily locates the valve stem without disturbing the key segments, locates the valve key grooves on the stem, positions and seats the keys in the grooves, and which is effective to position and seat the valve keys in the small circular type of grooves as well as in the larger types of grooves.

A still further object of the invention is to provide an improved valve spring key inserter which is relatively inexpensive to manufacture, which provides a great saving in time and labor in replacing the split conical keys on the valve stems of internal combustion engines, which may be employed in very restricted locations, which is sturdy in construction, which may be employed under unfavorable conditions, and which may be employed to mount different kinds, sizes and shapes of split keys on valve stems.

Further objects and advantages of the invention will become apparent from the following description and claims, and from the accompanying drawings, wherein:

Figure 1 is a top plan view of a valve spring key-inserting tool constructed in accordance with the present invention;

Figure 2 is a longitudinal cross-sectional view taken through the tool of Figure 1, showing the position of the tool immediately subsequent to the placement of the split keys upon a valve stem;

Figure 3 is a fragmentary plan view similar to Figure 1, showing the position of the movable jaw elements of the tool as said tool is being removed from engagement with the split keys subsequent to the mounting of the keys on the valve stem;

Figure 4 is a perspective view of the retractable separator member employed in the tool of Figure 1;

2
Figure 5 is an enlarged cross-sectional view taken on line 5—5 of Figure 1.
Referring to the drawings, 11 designates the main body portion of the tool, said main body portion being made of flat bar stock. The rear end portion of body 11 is reduced in width and is bent under to define a handle loop 12. The forward end portion of body 11 is bent upwardly at 13 and is again bent at 14, to define a forwardly-extending body portion 15, which also provides a base for mounting additional elements of the mechanism. The main portion of body 11 is inclined downwardly and rearwardly with respect to forward portion 15, as shown in Figure 2.

The forward body portion 15 is formed with a longitudinal centered notch 16 defining spaced fingers 17, 17, the forward ends of the fingers being smoothly rounded, as shown at 18. Secured to portion 15 and spaced symmetrically on opposite sides of the longitudinal center line of body 11 are the upstanding pins 19, 19. Secured to said portion are additional upstanding pins 20, 20, said pins 20, 20 being also symmetrically spaced on opposite sides of said center line and being located rearwardly of pins 19, 19. Engaged on the pins 19, 19 are the flat block members 21, 21, said block members being formed with the respective rearwardly-convergent, inclined edge surfaces 22, 22 located rearwardly adjacent the end of the notch 16, defining a ledge Z.

Located on the longitudinal center line of the main portion of body 11 are the spaced upstanding pins 23 and 24. Designated at 25 is a slide member formed with an upstanding rear lug 26 and with an upstanding forward portion 27 carrying a horizontal forwardly-extending blade 28. The main body of slide member 25 is slidably positioned on the main portion of body 11 and is formed with a first longitudinal slot 29 slidably receiving the pin 23. The rear portion of member 25 is formed with another longitudinal slot 30 slidably receiving pin 24. Forwardly adjacent slot 30 the member 25 is formed with a spring housing 31 containing a coil spring 32 bearing at its rear end on pin 24 and bearing against the end wall of housing 31 at its forward end, thereby biasing slide member 25 forwardly to bring upstanding portion 27 in abutment with the upwardly-bent portion 13 of body 11 and bringing the tip of blade 28 across the ledge Z, whereby it projects over the end of notch 16. A cotter pin 33 is provided on pin 24 to retain the slide member 25 in position on body 11. The blade 28 extends slidably between uprights Y,

Y, continuing onwardly between the flat block members 21, 21 and normally projects across ledge Z and over the end of the notch 16.

Designated at 34, 34 are respective arms formed with longitudinal slots 35', 35' slidably and pivotally receiving the pins 20, 20. Secured to the rear ends of arms 34, 34 are respective coil springs 35, 35 whose rear ends are secured to the rear portion of body 11 at 36, 36, biasing the arms 34, 34 rearwardly. The arms 34, 34 have respective inwardly-curved forward extensions 37, 37, with inclined inner surfaces W, W, terminating in rearwardly-directed lugs 38, 38. Arms 34, 34 are also formed with opposing lugs X, X, shown in Figure 3. The side edges of body portion 15 are formed with upstanding lugs 39, 39 in which are secured the rear ends of forwardly-extending leaf springs 40, 40 bearing on respective extensions 37, 37 and biasing said extensions inwardly. Secured on the pins 19, 19 and 20, 20 is a top cover plate 41 which overlies the springs 40, the arms 34, the blade 28, and the blocks 21, as shown in Figures 1, 2 and 5.

The rear ends of the arms 34, 34 are formed with respective outwardly-extending lugs 42, 42. Pivotally connected to each lug is a rearwardly-extending link bar 43 formed with a widened rear end portion 44. Each end portion 44 has a rear upstanding lug 46. Each end portion 44 is also formed with a longitudinal slot 45 which slidably and pivotally receives the shank of a headed bolt 47 secured to body 11.

The valve stem is shown at 48 in Figure 2. The valve spring is shown at 49 and the spring retainer is shown at 50. The split conical key segments are shown at 51, 51. In inserting the key segments, the retainer 50 is first lifted by means of a suitable slotted lifter 52.

To load the tool preparatory for use, arms 34, 34 are pushed forward and extensions 37, 37 are rotated outwardly to positions over fingers 17, 17 by pressing members 43 together intermediate pivots 42 and 47. The key segments are then deposited in upright position, with their large ends down, on the fingers 17, 17, thus being cradled in the curved portions of extensions 37, 37. Spring tension is then allowed to bring arms 34, 34 back, to securely anchor the key segments between inclined surfaces W, W and terminal lugs 38, 38 of extensions 37, 37 on the one side, and between the inclined surfaces 22, 22 of blocks 21, 21 on the other side. Guide fingers 17, 17 in addition to ledge Z provide base support for the key segments at right angles to the aforementioned holding means. Blade 28 is permitted to remain in its normal forward position projecting over the end of notch 16 for the loading operation.

The loaded tool is firmly held by handle loop 12, and the key segments are rotated apart by the action of arms 34, 34 through the application of pressure applied between thumb and forefinger on arms 43, 43. The tool is then advanced toward valve stem 48, which is located by fingers 17, 17. With further advancement of the tool, the projecting end of blade 28 locates the valve stem groove and is pushed back, permitting the key segments to be closed into the groove. Blade 28 and lugs 38 are then retracted from between the key segments. This retraction may be effected by engaging a crooked forefinger behind lugs 46 and engaging the thumb in front of lug 26 and applying pressure, thus simultaneously retracting lugs 38 and blade 28. The symmetrical convergent surfaces 22, 22 of blocks 21, 21 then move the key segments into fully seated positions

in the valve stem groove, whereupon retainer 50 may then be lowered over the key segments 51, 51, thus engaging the segments and locking them on the stem. Retainer 50 may contact the tool and push the tool downwardly over the key segments, since the tool has previously been freed from the recess in the stem. This completes the insertion of the key segments. The tool is removed by pressing inwardly on arms 43, 43, and since the segments 51, 51 are now firmly engaged and lugs 38 and blade 28 cannot engage therebetween, extensions 37, 37 swing outwardly clear of the valve stem, permitting removal of the tool. The same operation may be repeated for the remaining valves.

Fingers 17, 17 function as guides in locating the valve stem and in advancing the tool upon it. They further function as a base or floor to receive the key segments in loading the tool. In addition, said fingers respectively constitute one element of a triple-element abutment and anchorage system for holding each key segment. The other two elements are provided respectively by the inclined surfaces W, W of extensions 37, 37, and by the inclined convergent surfaces 22, 22 of blocks 21, 21 in conjunction with lugs 38, 38 and blade 28. A further function of surfaces 22, 22 of block 21, 21 is to drive the key segments into seating positions in the valve stem groove upon withdrawal of blade 28 and lugs 38, 38. Ledge Z functions as a supporting base in controlling the key segments as they are rotated by the action of extensions 37, 37, and are caused to present their curved inner contours in favorable positions for locating and entering the valve stem groove. A further function of ledge Z is to define, with inclined surfaces 22, 22, one of the anchorage elements of the above-mentioned three-element system.

Spring tension holds the movable parts in their normal closed positions, which also are the positions assumed by the parts in closing the key segments into the valve stem groove. The operating linkage provides for either independent or simultaneous movement of arms 34, 34 by pressing arms 43, 43 between thumb and forefinger of the hand holding the tool in its grasp.

The key segments themselves serve as parts of the mechanism for their own insertion by functioning as jaws which open to receive the valve stem and close upon said stem when the segments are properly located in their grooves. The segments further function as radius arms defining the rotary movement imparted by arms 34, 34. Said key segments also function as groove finders and as position locators by the presentation of their curved inner contours as they pivot on their rearward corners in the tool.

The above-mentioned triple-element anchorage system permits determination of proper groove positioning of the key segments by means of the sense of touch, whereby the key segments are not seated until their positioning is correct, thereby insuring a successful operation.

In the case of very small circular valve stem grooves into which blade 28 cannot enter, the key segments function as the groove finders and position locators.

Retractable separator blade 28 functions as one point in the anchorage system of the key segments and also as a point of control in loading the tool. Furthermore, it functions as a pivot on which the key segments rotate as jaws in opening for insertion and in closing upon the valve stem. In addition, blade 28 also functions as a

groove finder in the case of the larger or body type of grooves. A further function of blade 28 is to provide secure seating of the key segments after they are closed into the groove, through withdrawal of said blade 28 which permits convergent surfaces 22, 22 of blocks 21, 21 to force the keys home to a seat in the groove.

The downward and rearward inclination of the main portion of body 11 with respect to the forward portion 15 thereof permits clear vision 10 of the valve stem and the key segments at all times during the insertion of the segments.

Although a specific embodiment of a valve spring key-inserting tool has been disclosed in the foregoing description, it will be understood that various modifications within the spirit of the invention may occur to those skilled in the art. Therefore, it is intended that no limitations be placed upon the invention except as defined by the scope of the appended claims.

What is claimed is:

1. A split valve key-inserting tool comprising a flat body member having an offset flat end, said end being formed with an axially extending notch defining a pair of parallel positioning fingers engageable transversely on the outer surfaces of a valve stem, a pair of block members mounted in spaced side by side relation on said end at the inner end of the notch and spaced symmetrically from the axis of said notch, said block members having complementary faces forming an obtuse angle therebetween, a blade member slidably disposed on the end between the block members for axial movement to a forward position overlying said notch and between the fingers, an actuating member slidably mounted for axial movement on the body member and connected to the blade member, spring means operatively connected to the actuating member for urging said blade member to said forward position on the end, a pair of complementary hook members slidably and pivotally secured to said end symmetrically around said block members, said hook members being mounted for individual rectilinear movement on the fingers and outward curvilinear movement therefrom, inwardly directed lugs formed on the forward ends of said hook members, spring means carried by the outer edges of the end of the body member and engageable with said hook members for urging said lugs together to a position over said notch and substantially aligned with the blade, a pair of link bars slidably and pivotally mounted on the body member for axial and curvilinear movement and pivotally connected to the hook member, and spring means connected between the body member and each of the hook members for urging the lugs inwardly of said notch.

2. A split valve key-inserting tool comprising a flat body member having an offset flat end, said end being formed with an axially extending notch defining a pair of parallel positioning fingers engageable transversely on the outer surfaces of a

valve stem, a pair of block members mounted in spaced side by side relation on said end at the inner end of the notch and spaced symmetrically from the axis of said notch, said block members having their outer adjoining edges disposed at an angle so as to define a notch therebetween, a blade member slidably disposed on said end between the block members for axial movement to a forward position overlying said notch and between the fingers, an actuating member slidably mounted for axial movement on the body member and connected to the blade member, spring means operatively connected to the actuating member for urging said blade member to said forward position on the end, a pair of complementary hook members slidably and pivotally secured to said first named end symmetrically around said block members, said hook members being mounted for individual rectilinear movement on the fingers and outward curvilinear movement therefrom, inwardly directed lugs formed on the forward ends of said hook members, cantilever spring means carried by the outer edges of the end of the body member and engageable with said hook members for urging said lugs into abutment one with the other in a position over said notch and substantially aligned with the blade, said forward ends of the hook members being cooperatively disposed with respect to the notches on the blocks, a pair of link bars each having one end pivotally and slidably mounted on the body member for axial movement and having the other end thereof pivotally connected to the hook member at the end remote from said lugs, spring means connected between the body member and each of the hook members at said remote ends, and means formed on the ends of said link bars, whereby said bars may be urged forwardly to disengage the lugs, whereupon 40 said hook members may be swung outwardly, thereby freeing said tool for removal from the valve stem.
